VISE

Charles M. Gearing, Meriden, Conn., assignor to
 The Charles Parker Company, Meriden, Conn.,
 a corporation of Connecticut

Application March 5, 1942, Serial No. 433,487

3 Claims. (Cl. 81—33)

This invention relates to an improvement in bench-vises in which a movable jaw is operated by a screw coupled with the movable jaw and engaging with a nut mounted or formed in the vise-body.

The object of this invention is to provide simple and effective means for firmly coupling the operating-screw with the movable jaw, and the invention consists in the construction and arrangement of parts as hereinafter described and particularly recited in the claims.

In the accompanying drawings, in which certain modes of carrying out the present invention are shown for illustrative purposes:

Fig. 1 is a side view of a vise embodying this invention;

Fig. 2 is a front view of the same;

Fig. 3 is a sectional view on the line 3—3 of Fig. 2;

Fig. 4 is a sectional view on the line 4—4 of Fig. 3;

Fig. 5 is a perspective view of the movable jaw, detached;

Fig. 6 is a perspective view of the coupling-yoke, detached;

Fig. 7 is a perspective view of the finishing-plate, detached;

Fig. 8 is a perspective view of another form of coupling-yoke;

Fig. 9 is a side view showing part of the movable jaw of a vise, to illustrate a modified form of means for interlocking a coupling-yoke with the said jaw; and

Fig. 10 is a perspective view of the coupling-yoke shown in Fig. 9, detached.

The vise comprises a base 10, a fixed jaw 11, a movable jaw 12 and an operating-screw 13. The base 10 is adapted to be secured to a bench or other surface in the usual manner, and the fixed jaw 11 may be formed integral therewith or secured thereto in any suitable manner, and is provided with the usual guide-opening 14 for the slide 15 of the movable jaw 12 which is formed with a recess 16 to clear a nut 17 forming part of the fixed jaw 11, the said nut to be entered by the operating-screw 13. This screw is provided with a head 18, the inner face of which is seated in a recess 19 in the front face of the jaw 12, and the head 18 is formed near its inner end with an annular groove 20, for the reception of a coupling-yoke 21 which may be formed by stamping from sheet steel.

The lower ends of the yoke 21 are preferably formed with beveled edges 22—22 to engage with reversely-beveled notches 23—23, and the yoke 21 is secured to the front face of the movable jaw 12 by a screw 24, which also holds in position a finishing-plate 25 which may be of cast

metal and which also serves to prevent filings or other material from entering the groove 20, which is preferably wider than the thickness of the yoke 21 so as to prevent the yoke from binding when the head 18 is turned. The head 18 is provided with the usual handle 26.

Instead of forming the coupling-yoke 21 and the finishing-plate 25 in two parts, they may be formed in one piece as shown in Fig. 8, or a yoke 27 may be formed with arms 28 terminating in fingers 29 to enter notches 30 formed for them in the sides 31 of the movable jaw, as shown in Figs. 9 and 10 of the drawings. In either construction, the coupling-yoke is connected with the movable jaw not only by a screw but by the engagement of the ends of the yoke with notches formed in the movable jaw to receive them.

A firm connection is thus formed between the head of the screw and the movable jaw which connection will withstand the strain and wear to which it is subjected particularly in larger sizes of vises.

I claim:

1. A vise comprising fixed and movable jaws combined with a screw by means of which the movable jaw is moved inward or outward, said movable jaw formed in its outer face with notches, said screw provided with a head formed near its inner end with an annular groove, and a coupling-yoke secured to the movable jaw above the screw and extending into said groove and having its ends entered into said notches in said movable jaw.

2. A vise comprising fixed and movable jaws combined with a screw by means of which the movable jaw is moved inward or outward, said movable jaw formed in its outer face with beveled notches, said screw provided with a head formed near its inner end with an annular groove, and a flat sheet-metal coupling-yoke having beveled ends, said yoke secured to the movable jaw above said screw and extending into said groove and having its ends entered into said notches in said movable jaw.

3. A vise comprising fixed and movable jaws combined with a screw by means of which the movable jaw is moved inward or outward, said movable jaw formed in its outer face with beveled notches, said screw provided with a head formed near its inner end with an annular groove, a flat sheet-metal coupling-yoke having beveled ends, said yoke secured to the movable jaw above said screw and extending into said groove and having its ends entered into said notches in said movable jaw, and a finishing-plate over said yoke and extending over said groove.

CHARLES M. GEARING.
